(57) **CLAIM**

The ornamental design for the retainer tip hook, as shown and described.

DESCRIPTION

FIG. 1 is a front perspective view of a retainer tip hook showing my new design, attached to a back plate;

FIG. 2 is a front perspective view of the retainer tip hook shown in FIG. 1;

FIG. 3 is a left elevational view thereof, the right elevational view being a mirror image thereof;

FIG. 4 is a top plan view thereof;

FIG. 5 is a bottom plan view thereof.

FIG. 6 is a rear elevational view thereof; and,

FIG. 7 is a front elevational view thereof.

The broken lines immediately adjacent the full line portion of the hook represent the bounds of the claim and all other broken lines are for illustrative purposes only. None of the broken lines form a part of the claimed design.
